UNITED STATES PATENT OFFICE.

RICHARD H. GAY, OF WASHINGTON, DISTRICT OF COLUMBIA.

HOLDER FOR CHECKS AND VOUCHERS.

1,377,415.

Specification of Letters Patent.

Patented May 10, 1921.

Application filed November 30, 1920. Serial No. 427,446.

To all whom it may concern:

Be it known that I, RICHARD H. GAY, a citizen of the United States, residing at Washington, in the District of Columbia, have invented a new and useful Holder for Checks and Vouchers, of which the following is a specification.

The object of my invention is to provide a convenient device for holding a pile of checks in position so that one check may be readily withdrawn at a time, or the face of the various checks be examined without disturbing the order in which they are arranged. I attain these and other objects of my invention by the device illustrated in the accompanying drawings, in which—

Figure 1 is a top plan view; Fig. 2 is a side elevation; and Fig. 3 is a rear elevation.

Like characters of reference indicate like elements in the several views.

Referring to the accompanying drawings, I provide a suitable base 1 to which holder plate 2 is hinged at one end by hinges 3. Member 2 is held in its normal inclined position by a suitable spring 4. At the other end of the base 1 from the hinge 3, I provide a suitable wire holder 5, bent in the form shown in the drawings and having its free end extending transversely of the holder 2 and engaging one or more checks C on the holder 2. Member 5 is of general V-shape when viewed in side elevation, and has its ends inturned and pivotally mounted in suitable eyes 6 on the base 1.

In operation, the checks are slid under the wire 5, which functions to releasably hold them in place on the holder plate 2, in the manner shown in Figs. 1 and 2. In this position they may be readily examined and any desired check may be withdrawn without disturbing the others. The spring 4 functions to resiliently hold the plate 2 in frictional engagement with the wire 5.

I may modify the position of the spring or resilient means described; and I may also modify the shape and position of the wire check holding element, or adopt an equivalent member for performing the function

described and attributed to this member; and I may dispose said member through a suitable slot in the inclined plate instead of shaping it to extend around the end of the plate, said modification being suggested as an available equivalent structure, not involving a departure from my invention as hereinbefore described.

An important advantage of my device is that it can be conveniently used or operated with one hand by a person who is engaged in operating an adding machine or otherwise has one hand occupied.

What I claim is:

1. In a holder for checks and vouchers, the combination of a base, a holder plate hingedly attached to the base, a spring holding the plate in its normal inclined position relative to the base, and a wire element pivotally mounted on the base at a position a considerable distance inward from the free end of the hinged plate and extending rearwardly over its free end and bent directly forward parallel with the inclined plate, whereby the end of the inclined plate will bear against said forwardly bent portion when the plate is released after being depressed.

2. In a holder for checks and vouchers, the combination of a base, a holder plate hingedly attached to the base, a spring holding the plate in a normal inclined position relative to the base, a wire element pivotally mounted on the base at a position inward from the free end of the hinged plate and extending rearwardly over the free end of the hinged plate and then bent forwardly in alignment with the hinged plate, and then in approximate U-shape, to form a voucher engaging element, whereby the insertion of additional paper and the depression of the hinged plate will not in releasing the wire element from engagement with the papers on the hinged plate throw same to a position off the plate, whereby to prevent scattering of papers on the device.

RICHARD H. GAY.
